W. W. MIRON

ELECTRIC FURNACE SIGNAL

Filed July 3, 1919

WITNESSES

Chas. H. Young,
J. Howes Webster

INVENTOR

UNITED STATES PATENT OFFICE.

WALTER W. MIRON, OF OAKLAND, CALIFORNIA.

ELECTRIC-FURNACE SIGNAL.

Application filed July 3, 1919. Serial No. 308,604.

To all whom it may concern:

Be it known that I, WALTER W. MIRON, a citizen of the United States, residing at Oakland, in the county of Alameda and State of California, have invented certain new and useful Improvements in Electric-Furnace Signals, of which the following is a specification.

The object of my invention is to provide an electrically operated, automatic signal system. The purpose particularly of the device is its use in an electric metal melting furnace as a telltale signal upon the contact of the electrode with a solid body of metal in the bottom of the furnace, or contact with the bottom of the furnace.

The invention is so constructed that it may be adapted for use in conjunction with a furnace having any number of electrodes which might be operating in a furnace and I do not confine myself to any particular number of electrodes to which my system might be adapted.

I utilize an ordinary electric bell which gives warning of the contact between the solid metal and electrode, an annunciator drop indicates the particular electrode in contact with the metal being melted or the bottom of the furnace. The invention is extremely simple and the following specifications will enable anyone to construct this invention who is familiar with the art to which it appertains.

Referring to the drawings in which like numerals designate like parts in all the views; Fig. 1 is a front view of the device. Fig. 2 is a side view, Fig. 3 a typical wiring diagram of the device as applied to a metal melting furnace utilizing four electrodes for the production of heat, and Fig. 4 shows another position in which the invention can be applied to an electro metal melting furnace.

Referring to the several views, the contactor, 1 is shown clearing part of the frame 16 of the furnace. The contactor 1 is fastened in a secure manner to the insulated bracket block 2, by the bolts and nuts 20. The insulated bracket block 2 is held in a rigid position by the U clamp bolt and nuts 3, the bolt embracing the guide pin 4. Electrical connection is made to contactor 1 by the insulated wire 5. Insulated wire connections 6, 7, and 8, are connected to other elec-

trodes not shown. The annunciator drops 9 indicate the particular electrode which has come in contact with the solid metal or bottom of the furnace 21. The signal bell 10, is of the ordinary construction, and is connected in such a manner that the closing of the circuit causes it to ring. Incandescent lamps 11, are connected in multiple series the purpose of which is to reduce the line voltage. It has been found in practice that by having 110 volts alternating current with three 54 watt lamps, 11 in series on the main annunciator feed wires 23, there is obtained 70 volts drop on the line and the alternating current flowing through the system operates the six volt direct current bell 10 and the annunciator 9 in series. The electrical system is thrown out of service with the main feed wires 23, by the single pole switch 12. The electrode carrying arm 13 is connected with a shaft not shown in the drawings and which moves the electrode carrying arm 13, thereby causing the electrode carrying arm 13 to raise and lower the electrode 17. The electrode carrying arm 13, travels between the two channel irons of the frame 16, and is held in position by the guide wheels 14 turning on the guide wheel pins 24; and the guide pins 4, and 15, which are in contact with the frame 1. The carbon electrode 17, or any other suitable material, is fastened in a secure and rigid manner to one end of the electrode carrying arm 13. The furnace 18 is a type of electric furnace used for the melting of metals. The U bolt 3 and nuts 19 hold the bracket insulated block 2 in a rigid manner to guide pin 4. The wiring system is grounded on the frame of the furnace at 22. The metal in the bottom of the furnace is shown by 21.

Having thus described the component parts of my invention, I will describe the operation of the invention, the main object of the device is to give warning at the time contact takes place between the electrode 17 and the metal 21 or between the electrode 17 and the bottom of the furnace. In practice it is found that if the electrode comes in contact with a solid hard substance, and the electrode carrying arm 13 continues its downward movement there is no alternative but that the electrode 17 must break thereby being destroyed causing considerable ex-

pense and delay, which I claim that my invention is adapted to overcome in the following manner.

If the electrode 17 on being fed down into the furnace, should make contact with the solid metal 21, or the bottom of the furnace 18, it would cause the electrode 17 and the electrode carrying arm 13 to tilt (due to poor connections in the mechanism) and move outward. As the contactor 1 is fastened to the electrode carrying arm 13, and the pin 4, by means of the U bolts and nuts 19 and insulated from the bracket block 21, it would, due to the small clearance between it and the frame 16 make a contact with the frame 16, thus closing the circuit and causing the bell 10 to ring and the annunciator 9, to drop and thereby give a positive signal of the particular electrode in contact with the solid body of the metal in the furnace. It has however been found in practice that no particular harm can result where the electrode comes in contact with metal when in a molten state and does not touch the bottom of the furnace.

It is found in practice that my invention does all that I claim it will do, and the construction is extremely simple, inexpensive, and practical. It is readily adapted to any

particular furnace in use; as I do not confine myself to any particular make of furnace or kind.

Having thus described my invention, what I claim as new and useful and desire to secure by Letters Patent is:

1. In an electric furnace, the combination with a movable electrode; of a supporting arm carrying said electrode, a support on which the arm is slid able and also free to tilt upon contact of the electrode with an obstruction, an electro-responsive signal device, and a switch controlling said device and operated by the tilting movement of the aforesaid arm.

2. In an electric furnace, the combination with a movable electrode; of a supporting arm carrying said electrode, a support on which the arm is slid able and also free to tilt upon contact of the electrode with an obstruction, an electro-responsive signal device, an energizing circuit for said device grounded on the aforesaid support, and a switch blade carried by the aforesaid arm, said blade making contact with the support when said arm tilts.

In testimony whereof I affixed my signature.

WALTER W. MIRON.
